SHIFT LEVER KNOB

Wayne R. Howard, Jackson, Mich., assignor to Clark
Equipment Company, a corporation of Michigan

Filed Aug. 22, 1958, Ser. No. 52,348

Term of patent 14 years

(Cl. D14—6)

FIG. 1

FIG. 2

FIG. 3

FIG. 4

FIG. 5

FIG. 6

Figure 1 is a top plan view of a shift lever knob showing my new design;

Figure 2 is a front elevational view showing the same shift lever knob;

Figure 3 is a view of the same shift lever knob from one end;

Figure 4 is an end view of the other end of the shift lever knob;

Figure 5 is a rear elevational view of the shift lever knob; while

Figure 6 is a bottom plan view of the shift lever knob.

I claim:

The ornamental design for a shift lever knob, substantially as shown.
